UNITED STATES PATENT OFFICE

2,623,528

LOCK FOR COMPRESSOR PLATES

Ralph R. Uhrmacher and Eremelio Cairelli, Chicago, Ill., assignors to Wilson-Jones Company, Chicago, Ill., a corporation of Massachusetts

Application February 24, 1947; Serial No. 730,522

6 Claims. (Cl. 129—26)

1

This invention relates to a lock for compressor plates, particularly useful in connection with filing or posting trays.

In filing or posting trays it is essential to have the sheets in easily accessible position in the tray when an operator is using the tray. However, it is often desirable to have rapid efficient locking means to protect the sheets from prying eyes of unauthorized people whenever the operator leaves the trays unattended for a short time.

It is an object of our invention to provide simple and efficient locking means that may be easily manipulated to lock or to unlock the compressor plates on a filing or posting tray. It is a further object of our invention to provide locking means that does not require any extra key, but may be operated with the same key required to move the compressor plates in the ordinary operation of the tray. Other objects of our invention will become apparent upon reading the following description, taken in conjunction with the accompanying drawings, in which:

Figure 1 is a side elevational view of a tray embodying the invention with the compressor plates in locked position and parts of the side rail of the tray broken away to facilitate the illustration;

Figure 2 is a cross sectional view through one of the compressor plates and its locking structure;

Figure 3 is a top elevational view of the tray shown in Figure 1;

Figure 4 is a detail perspective view of the locking structure for one compressor plate;

Figure 5 is a cross sectional view of a compressor plate and its associated locking structure showing the compressor plate in open position providing easy access to the sheets or cards positioned in the tray;

Figure 6 is a view, similar to Figure 5, showing the compressor plate moved vertically towards locking position;

Figure 7 is a view, similar to Figure 5, showing the compressor plate moved past the vertical position, ready to be locked;

Figure 8 is a view, similar to Figure 5, showing the compressor plate in locked position;

Figure 9 is a fragmentary cross sectional view showing a modified form of locking mechanism in the open position similar to that shown in Figure 5;

Figure 10 is a cross sectional view taken along the line 10—10 of Figure 9; and

Figure 11 is a view, similar to Figure 9, showing the modified form of locking mechanism in locked position.

The locking structure is described in connection with the type of posting tray which constitutes the subject matter of an application Serial No. 626,316 filed November 2, 1945, by

2

Samuel Segal, which issued as Patent No. 2,520,733 on August 29, 1950. Since the tray structure is fully described in that application and does not constitute any part of the present invention it will be referred to in general terms only. It will be obvious that the advantages of the locking structure described herein are not limited to the specific tray mentioned, but may be attained with any posting tray or any filing tray or similar structure having a movable compressor plate.

In the drawings, the reference numeral 2 indicates a tray having a pair of compressor plates 3. Each compressor plate is mounted on a block 5 having a transverse opening 6 threaded to engage threads 8 on a rod 7. Each rod 7 has one end 9 journaled near the center of the tray and its other end journaled in a bearing 9 at the end of the tray. The bearing 9 is provided with an opening 10 to make the end of the rod 8 accessible to a key or crank of conventional type. The end 11 of the rod 8 is provided with a non-circular projection 12 adapted to fit into the recess in the key or crank so that rotation of the key or crank will rotate the rod 8 and thereby move the compressor plate 3 longitudinally of the tray. In the tray structure described each compressor plate is moved separately, but it will be understood that both compressor plates may be mounted on a single rod threaded in opposite directions from its center so that both compressor plates are moved simultaneously by rotating the single rod.

The compressor plates and their associated locking structure are duplicates of each other, and, therefore, only one will be described. Each compressor plate has an angle shaped bracket 13 hinged to plate 3, as indicated at 14. Latching means are provided for normally holding the compressor plate in vertical position or in predetermined angular positions permitting easy reference to the sheets contained in the tray. The latching means includes a link 15 pivoted between a pair of ears 16, as indicated at 17. The ears 16 are welded or otherwise rigidly secured to the base portion of the angle member 13. The upper end of the link 15 fits telescopically into a tubular sheath 18. The upper end of the sheath 18 is pivoted between a pair of ears 19, as indicated at 20. The ears 19 are permanently secured to the plate 3 by welding, or in any other suitable manner.

The upper end of the link 15 is provided with a plurality of notches 21 and 21' on its edge spaced farthest from the plate 3. The tubular sheath 18 is provided with a notch 22 that extends transversely from the edge farthest from plate 3 approximately half way through the sheath. A handle 23 has a bottom portion 24 provided with a substantially rectangular open-

ing 25 through which the sheath 18 projects. The handle 23 also includes an arcuate hand grasping portion 26 and an upper portion 27 substantially parallel to the plate 3. The arcuate portion 26 is provided with a pair of depending ears 28 which are pivoted to the ears 19 and the upper end of the sheath 18 by the pivot pin 20. The ears 28 are preferably welded to the arcuate portion 26 of the handle, but they may be integral therewith or may be secured by riveting.

The upper portion 27 is provided with a deep cup shaped portion 29 having its open top adjacent the plate 3. The cup shaped portion may be integral with the handle or may be formed by spinning a separately formed cup member in a suitable aperture. A coiled compression spring 30, seated in the recess of the cup 29, bears against the plate 3 and urges the upper portion 27 of the handle outwardly, thereby pushing the bottom portion 24 of the handle into the notch 22 with which it registers. When the link 15 reaches one of the predetermined positions the bottom 24 moves into engagement with one of the notches 21 or 21'.

The bottom edge of each notch 21 and 21' is perpendicular to the edge of the link so that it will abut the forward edge of the bottom portion 24 of the handle adjacent the edge of the opening 25 farthest from the plate 3 and prevent further movement of the link, and the plate 3, in an outward direction. The top edge of each notch 21 is slanted so that if the movement of the plate 3 is towards the compressing position the forward edge of the portion 24 adjacent the edge of the opening 25 rides out of the notch 21 and the motion towards compressing position is not stopped until the top notch 21' is reached. Notch 21' has its top edge parallel to its bottom edge so the forward edge of the portion 24 adjacent the opening 25 can not ride out of the top notch. In order to move the plate 3 outwardly when the edge of portion 24 adjacent the opening 25 is engaged with one of the notches 21 it is necessary to press the cup 29 against the action of spring 30 to release the edge from the notch, and then pull the handle 23 outwardly before the pressure against the spring 30 is released.

In the embodiment of the present invention illustrated in Figures 1 to 8 of the drawings, the forward edge of the portion 24 of the handle adjacent the edge of the opening 25 farthest from the plate 3 is provided with an upturned locking projection 31. The projection 31 is preferably integral with the handle, but may be welded or secured to the portion 24 in any suitable manner. The action of the projection 31 may best be understood from a study of Figures 5 to 8 inclusive.

When the plate 3 is opened outwardly in reference position, as shown in Figure 5, the projection 31 engages the slanting top edge of the bottom notch 21. Movement of the plate 3 towards 65 compressing position causes the projection 31 to ride out of the notch 21 and continue upwardly, relative to the link 15, until it reaches the top notch 21'. If the compression plate is far enough away from the sheets to be compressed, the plate 3 can be forced slightly past the vertical position, with the locking projection 31 engaged in the top notch 21', as indicated in Figure 7.

When the plate 3 is in the position shown in 75

Figure 7, rotation of the rod 7 in the proper direction moves the compressor plate structure towards the sheets and forces the plate 3 into vertical position by moving the angle member 13 towards the sheets while movement of the plate 3 in the same direction is restrained by the sheets. This movement shortens the distance between pivots 17 and 20 slightly, thereby forcing the bottom portion 24 of the handle against the top wall of notch 22 with the locking projection 31 in the upper portion of top notch 21' which has been forced past the upper edge of notch 22.

In this position the projection 31 locks the plate 3 against outward movement because pressure on the cup 29 can not force the projection 31 past the top edge of notch 22. In order to open the plate 3 outwardly from the locked position it is necessary to rotate the rod 7 in opening direction, and this can be done only by the key or crank which may be retained by the operator if he has to leave the tray unattended. If the rod 7 is rotated in the opening direction 25 Figure 7 and the handle 23 may be manipulated to open the plate 3 to reference position.

The embodiment of the invention shown in Figures 9, 10 and 11 differs from that previously described only in that the lip or projection 31 is omitted and the sheath 18' is provided with an enlarged portion or projection 32 on its side opposite the notch 22. The enlarged portion is preferably welded to the sheath 18', but may be secured in any suitable manner. During the 30 operation of the tray the bottom portion 24 of the handle is normally below and out of engagement with the enlarged portion 32 of the sheath 18'. When the plate 3 is moved from the position of Figure 7 to that of Figure 8, the shortening of the distance between the pivots 17 and 20 causes the link 15 to move upwardly a short distance into the sheath 18. The bottom of notch 21', in which the handle portion 24 is positioned, forces the handle portion 24 upwardly and 40 causes the aperture 25 to engage the enlarged portion 32. The enlarged portion 32 is of such size and shape that a cross section of the sheath 18' through the portion 32 is substantially the same as the cross section horizontally through the aperture 25, as shown in Figure 10. Therefore, when the aperture 25 engages the enlarged portion 32 pressure on the cup 29 can not release the forward edge of the portion 24 adjacent the side of the aperture 25 until the distance between the pivots 17 and 20 is lengthened by 50 rotating the rod 7 so that the aperture 25 is disengaged from the enlarged portion 32.

Although we have described two preferred embodiments of our invention in considerable detail, it will be understood that the description is intended to be illustrative, rather than restrictive, as many details may be modified or changed without departing from the spirit or scope of the invention. Accordingly, we do not desire to be restricted to the exact structure described, except as limited by the appended claims.

We claim:

1. In a posting tray, a compressor plate, a sheath pivoted to the upper portion of said compressor plate, said sheath having a notch in one edge thereof, a handle pivoted to said sheath, a bracket hingedly secured to the lower portion of said compressor plate, a link pivoted to said bracket, said link having a plurality of notches 70 in one edge thereof, said notches being adapted

to be successively aligned with the notch in said sheath as said compressor plate is moved pivotally relative to said bracket, said handle cooperating with the notch in said sheath and the notches in said link successively aligned with the notch in said sheath to releasably hold said compressor plate in various positions, including a compressing position wherein the upper edge of said compressor plate slants forwardly of the lower edge which is secured to said bracket, key operated means for moving said bracket inwardly a slight distance when said compressor plate is in compressing position, and locking means actuated by said additional inward movement of said bracket for positively locking said compressor plate in compressing position, said locking means comprising a projection extending laterally from said sheath engageable with said handle to prevent transverse movement of said handle relative to said sheath and being releasable only by reverse movement of said key operated means.

2. In a posting tray, a compressor plate, a bracket secured to the lower portion of said compressor plate, said compressor plate being normally movable pivotally relative to said bracket, a link pivoted to said bracket, said link being provided with a plurality of notches, a sheath pivoted to said compressor plate and engaging said link to cause pivotal movement of said compressor plate upon pivotal movement of said link, a handle engaging said notches and said sheath to releasably hold said compressor plate in a plurality of predetermined positions as said compressor plate is moved pivotally relative to said bracket, the last position of said compressor plate as said plate is moved inwardly being a compressing position in which the upper edge of said compressor plate slants forwardly of the lower edge which is pivotally secured to said bracket, key operated means for moving said bracket inwardly a slight distance after said compressor plate is in compressing position, and locking means actuated by said additional inward movement of said bracket for locking said compressor plate against pivotal movement relative to said bracket, said locking means comprising a projection extending laterally from said sheath engageable with said handle to prevent transverse movement of said handle relative to said sheath and being releasable only by reverse movement of said key operated means.

3. In a posting tray, a compressor plate, a sheath pivoted to the upper portion of said compressor plate, a handle pivoted to said sheath, a bracket hingedly secured to the lower portion of said compressor plate, a link pivoted to said bracket, the upper portion of said link fitting in said sheath, a notch in said sheath, a portion of said handle projecting through said notch and engaging the upper portion of said link to hold said compressor plate in either reference or compressing position, said handle being normally operable to release said compressor plate from either of said positions, and key operated means for moving said bracket inwardly a slight distance after said compressor plate is in compressing position, and locking means actuated by said additional inward movement of said bracket for locking said compressor plate against release by the operation of said handle, said locking means comprising a projection extending laterally from said sheath and engageable with said handle to hold said handle against releasing movement.

4. In a posting tray, a compressor plate, a sheath pivoted to the upper portion of said com-

pressor plate, a handle pivoted to said sheath, a bracket hingedly secured to the lower portion of said compressor plate, a link pivoted to said bracket, said link telescopically fitting into said sheath, said handle cooperating with said sheath and said link to releasably hold said compressor plate in compressing position, a projection extending laterally from said sheath, and key operated means for moving said bracket inwardly when said compressor plate is in compressing position, said inward movement of the bracket causing said projection to engage said handle and thereby lock said handle against releasing movement.

5. In a posting tray, a compressor plate, a sheath pivoted to the upper portion of said compressor plate, a handle pivoted to said sheath, a bracket hingedly secured to the lower portion of said compressor plate, a link pivoted to said bracket, the upper portion of said link telescopically fitting into said sheath, said handle having an opening through which said sheath extends, a notch in said sheath, a portion of said handle adjacent said opening projecting into said notch and engaging said link to releasably hold said compressor plate in compressing position, an enlarged portion on said sheath positioned above said handle portion engaging said sheath, and a rod operatively connected to said bracket, movement of said rod urging said bracket inwardly when said compressor plate is in compressing position being effective to move said handle portion into engagement with said enlarged portion on said sheath, the engagement of said enlarged portion with said handle being effective to prevent releasing movement of said handle until said bracket has been moved outwardly by reverse movement of said rod.

6. In a posting tray, a threaded rod, a compressor plate mounted for longitudinal movement relative to said rod upon rotation of said rod, said plate being pivotally movable between reference and compressing positions, a handle, a sheath and a link, said handle and sheath being connected to the upper portion of said plate and said link being connected to the lower portion of said plate, said handle cooperating with said sheath and said link to releasably hold said plate in compressing position, and a projection extending laterally from said sheath, rotation of said rod in one direction when said plate is in compressing position changing the structural relationship between said handle and sheath to cause said handle to engage said projection and to thereby lock said handle against movement in a direction to release said plate from compressing position.
